SLITTING MEANS

Original Filed Jan. 12, 1929

Inventor
James A. Cameron

By his Attorney

Walt Beeken

UNITED STATES PATENT OFFICE

JAMES A. CAMERON, OF BROOKLYN, NEW YORK, ASSIGNOR TO CAMERON MACHINE COMPANY, OF BROOKLYN, NEW YORK, A CORPORATION OF NEW YORK

SLITTING MEANS

Original application filed January 12, 1929, Serial No. 332,037. Divided and this application filed April 9, 1930, Serial No. 442,754. Renewed December 10, 1931.

This invention relates to means for slitting webs of flexible material into longitudinal sections in the type of slitting machines usually referred to as "score-cut" slitting machines, and this application is a division of one filed January 12, 1929, Ser. No. 332,037, now Patent No. 1,865,302, dated June 28th, 1932.

The main object and feature of the invention is to provide means whereby a backing-roll having circumferential grooves can be arranged to slit flexible material into any desired widths notwithstanding the presence of said circumferential grooves.

In the accompanying drawing the invention is disclosed in a concrete and preferred form in which:

Fig. 1 is a somewhat diagrammatic side view, partly in section, of a slitting and winding machine embodying the invention;

Fig. 2 is a top plan view of the backing-roll shown in Fig. 1, with score-cut slitters shown associated therewith;

Fig. 3 is a detail sectional view substantially on the plane of line 3-3 of Fig. 2;

Fig. 4 is a detail sectional view substantially on the plane of line 4-4 of Fig. 3; and

Fig. 5 is a fragmentary view in perspective of one of the sheet-material rings and its anchoring means.

1^d indicates a backing-roll which, in the form here shown, is one of a pair of surface-winding drums supporting a winding shaft 7^a. Score-cut slitters 3 cooperate with said backing-roll to slit web 4 into longitudinal strips. These features are well understood in the art.

If now the backing-roll is provided with circumferential grooves as 31 and with lengthwise-extending grooves as 27, it will be seen that blank spaces must be left on the backing-roll to admit of engagement therewith of the score-cut slitters. This prevents the backing-roll from being entirely covered with grooves and limits the machine in that severed strips of any desired width cannot be produced in the same machine. To overcome this difficulty, I provide the backing-roll with an annular slitting member, preferably in the form of a sheet-material ring, 2^d, and

I make this ring adjustable lengthwise over the paper-engaging surface of said backing-roll so that it can cooperate with similarly adjustable score-cut slitters 3, said score-cut slitters being mounted independently of the 55 backing-roll. In this way the entire surface of the backing-roll may be provided with grooves, but, notwithstanding this, slitted sections of different widths may be produced. In order to anchor the ring in the position to 60 which it has been adjusted, I provide said ring with a spring portion 28 having a button 29 at its outer end, which button can be slipped into an aperture like 30 of which there may be any desired number in groove 65 27.

The grooves of the backing member are preferably of the type known as "Johnstone grooves" and are disclosed in Patents Nos. 1,355,106 and 1,355,107. 70

I claim:

1. In a slitting machine, a backing-roll having a circumferential paper-engaging surface provided with circumferential grooves, an annular slitting member mounted on and adjustable over said paper-engaging surface in a direction lengthwise of the roll, means to secure said annular member in the position to which it is adjusted, and a slitting member mounted independently of the 75 back-roll and adjustable lengthwise of the latter to engage the annular member in its differently adjusted positions.

2. In a slitting machine, a backing-roll having a circumferential paper-engaging surface provided with circumferential grooves, a sheet-material ring mounted on and adjustable over said paper-engaging surface in a direction lengthwise of the roll, means to secure said ring in the position to 80 which it is adjusted, and a score-cut slitting member mounted independently of the backing-roll and adjustable lengthwise of the latter to engage the ring in its differently adjusted positions. 85

3. In a slitting machine, a backing-roll having a circumferential paper-engaging surface provided with a plurality of circumferential grooves and a lengthwise-extending 90 groove, an annular slitting member mounted 95 100

on and adjustable over said paper-engaging surface in a direction lengthwise of the roll, locking means extending from the annular member and adjustably anchored in the lengthwise-extending groove, and a slitting member mounted independently of the backing roll and adjustable lengthwise of the latter to engage the annular member in its differently adjusted positions.

10. 4. In a slitting machine, a backing-roll having a circumferential paper-engaging surface provided with a plurality of circumferential grooves and a lengthwise-extending groove, a sheet-material ring mounted on and adjustable over said paper-engaging surface in a direction lengthwise of the roll, locking means extending from the ring and adjustably anchored in the lengthwise-extending groove, and a score-cut slitting member mounted independently of the backing-roll and adjustable lengthwise of the latter to engage the ring in its differently adjusted positions.
15. 5. The combination of a roll having a circumferential paper-engaging surface provided with a groove, an annular slitting member mounted on and adjustable over said paper-engaging surface in a direction lengthwise of the roll, and locking means extending from the annular member and adjustably anchored in the groove.

20. 6. A backing member for score-cut slitting means comprising: a roll having a circumferential paper-engaging surface provided with a groove, a sheet-material ring mounted on and adjustable over said paper-engaging surface in a direction lengthwise of the roll and locking means extending from the ring and adjustably anchored in the groove.

25. Signed at the borough of Manhattan, county of New York, city and State of New York, this 3rd day of April, 1930.

JAMES A. CAMERON.
